UNITED STATES PATENT OFFICE.

WILLIAM A. COOK, OF FRUITVILLE, FLORIDA.

PORABLE HEATER.

1,293,044.

Specification of Letters Patent.

Patented Feb. 4, 1919.

Application filed October 16, 1916. Serial No. 125,957.

To all whom it may concern:

Be it known that I, WILLIAM A. COOK, a citizen of the United States, residing at Fruitville, in the county of Manatee and 5 State of Florida, have invented certain new and useful Improvements in Portable Heaters, of which the following is a specification.

My invention relates to a heater and particularly to one of the portable type adapted 10 for the heating of branding irons.

The invention aims to provide a novel, improved and simplified construction of heater possessing the advantageous features of construction and utility, which will appear 15 from the accompanying drawings, considered in connection with the following description and which heater generally comprises a housing of relatively movable parts, the burner proper within the housing, means 20 to facilitate portage of the article, and means supported from said means and leading to the burner to feed fuel to the heater.

In said drawings:—

25 Figure 1 is a side elevation of the improved burner;

Fig. 2 is a vertical sectional view on the improved heater taken on the lines 2—2 of Fig. 1;

30 Fig. 3 is a cross sectional view on the lines 3—3 of Fig. 1, and,

Fig. 4 is a cross sectional view on the line 4—4 of Fig. 1.

Referring specifically to the drawings, 35 wherein like reference characters designate like or similar parts, a casing is provided forming a heating chamber and comprising sections 5 and 6 which sections are hinged together as at 7 for opening movement horizontally and which sections are adapted to 40 be fastened in closed relation or against independent movement by any suitable form of fastening means at 8. Bottom walls of the sections 5 and 6 are provided with suit-

45 able vent openings as at 9. A suitable staff or rod 10 is provided, being fastened as by means of solder to the top wall of section 5 and being provided with a suitable handle as at 11.

50 A fuel supply tank 12 is provided from which the supply tube or pipe 13 leads interiorly of the casing 5—6 and which tube and tank are rigidly fastened to the staff 10

by means of bands 14 so that the tube will move with the staff and the section to which it is connected, without interfering with the swinging movement of the other section. Tank 12 may be of any suitable construction and it is capable of being filled through an opening disposed upon the removal of a filling cap or plug 15. The fuel used may be any suitable liquid hydrocarbon. In order to regulate the quantity of fuel supplied through tube 13, a valve 16 is provided which has an elongated stem 17 extending 65 through and above the top wall of the tank 12. Any suitable means may be utilized for maintaining the valve in adjusted position, for instance, it may be screw-threaded on the stem as at 18 so as to coöperate with 70 screw-threads within a boss 19 on the tank.

Within the casing formed of sections 5 and 6, the end of tube 13 is enlarged into a burner 20 in the wall of which suitable orifices or ports 21 are provided. In the top 75 walls of the sections 5 and 6, suitable openings 22 are preferably provided through which the igniting medium for the gas may be passed and also through which the branding irons to be heated from the burner at 20 may be inserted.

In use, the valve 16 is first regulated, with a supply of liquid fuel within the tank 12, by turning the rod 18. The screw-threads of this rod or stem will coöperate with those 85 within the boss 19 thus maintaining the valve in its adjusted position. A supply of fuel will now gravitate to the burner 20 and this may be ignited by passing a lighted match through one of the openings 22 and 90 in contact therewith or with the gas therefrom. The branding irons as stated may be inserted through the openings 22 and held relatively close to the burner 20 until the desired heat is attained. Since the fastening 95 8 permits opening of the sections 5 and 6, the burner 20 and the interior of the casing may be readily cleaned.

Since merely the preferred embodiment of the invention has been illustrated and described, it is to be understood that changes in the details of construction of the invention may be resorted to without departing 100 from its spirit and scope.

I claim:—

A portable heater, comprising a casing

105

having a plurality of small openings in its bottom and relatively large openings in its top, a staff connected to the top of the casing, a burner within the casing, a fuel tank 5 mounted on the upper end of the staff, and a conduit connecting the tank with the said burner and attached to the staff.

In testimony whereof I affix my signature in presence of two witnesses.

WILLIAM A. COOK.
